PROPELLER FOR AIRCRAFT

Heinrich Sukohl, Berlin-Waidmannslust,
GermanyApplication August 15, 1939, Serial No. 290,171
In Germany February 24, 1939

3 Claims. (Cl. 170—159)

My invention relates to improvements in propellers for air craft, and the object of the improvements is to provide a propeller which has low weight and high strength. With this object in view my invention consists in building the propeller blade upon a root portion formed with a transverse shoulder, and wrapping straps of high tensile strength around said shoulder and extending therefrom over the whole or a large portion of the length of blade and fixed thereto. In most cases a core or cores are provided internally of the said straps which core or cores substantially have the function to give the desired shape to the blade, while the said straps have the function to impart strength thereto and particularly to transmit the centrifugal force to the root and to take up bending and torsional forces. Therefore the core is preferably made from light material such as balsa wood, artificial sponge like material, and the like.

For the purpose of explaining the invention and example embodying the same has been shown in the accompanying drawing in which the same reference characters have been used in all the views to indicate corresponding parts. In said drawing,

Fig. 1 is an elevation of the blade of the propeller with some of the layers of straps removed,

Fig. 2 is a sectional elevation taken on the line 2—2 of Fig. 1,

Fig. 3 is a sectional plan view taken on the line 3—3 of Fig. 1,

Fig. 4 is an elevation showing the root of the blade, and

Fig. 5 is a sectional plan view similar to Fig. 3 and showing a modification.

In the construction shown in the drawing the propeller consists of a root comprising a cylindrical stem portion 1 adapted at its inner end to be fixed to the hub of the propeller, and at its outer end widened in a flat outwardly tapering portion 2 projecting laterally beyond the portion 1 to provide at the inner edge transverse shoulders 9, a core comprising a portion 3 fixed to the tapering portion 2 of the root and made from wood, and a portion 4 made from light material such as balsa wood and fixed to the portion 3, and straps preferably made from wood veneer of high tensile strength wrapped upon the transverse shoulders 9 of the root and extending thence longitudinally of the blade. The portions 2, 3 and 4 are preferably united by glueing or otherwise, and the parts 2 and 3 are further held together by additional straps as will now be de-

scribed. The root 1, 2 may be made from metal, hard wood, or reinforced artificial resins.

Around the part of the core portion 3 fixed to the portion 2 of the root straps 5 of wood veneer are wound transversely in one or more layers according to the desired strength. The said straps may be of relatively great length, wound spirally around the union of core 3 with the portion 2 of the root, as is shown in Figs. 1 and 4, or they may consist of relatively short pieces, each wound once around the core with the ends overlapping, as is shown in Fig. 5, in which latter case the overlapping ends of adjacent and superposed windings are preferably displaced with relation to one another. The object of the additional straps 5 is to fix the core 3 to the portion 2 of the root.

Around the laterally projecting shoulders 9 several plies of straps 6 are wound. One end of 20 each strap preferably extends from a line slightly beyond the outer end of the portion 2, indicated by the dotted line 7 in Fig. 1. From the line 7 the straps extend towards the root; they are wrapped around the shoulders of the portion 2; and they extend thence outwardly to the outer end of the propeller blade. Preferably the shoulders 9 of the portion 2 are disposed at such angles to the axis of the blade, that when the short ends 6' of the straps are disposed axially of the blade the longer ends thereof are disposed at a suitable angle to the axis, and so that the portions of the straps coming from opposite sides of the root cross each other. Preferably the long ends of the straps extending from the root to the 30 end of the blade are disposed at a small angle to the axis of the blade because thereby they are best able to take up the centrifugal forces. But for covering the leading and trailing portions of the blade the straps 8 of some of the plies are disposed at larger angles.

The plies of straps are glued to each other and to the core 3, 4.

In Fig. 1 some of the plies of straps have been broken away. In the left hand part of the figure 45 I have shown in full lines the long ends of the straps 6 extending from the root to the outer end of the blade, while the ends 6' are shown in dotted lines. On the right hand side the lateral plies of straps 6 have been partly broken away in order to show the inner transverse plies 5 and also portions 6' of another ply of straps.

As has been stated above the core substantially has the function to give the desired shape to the blade, and therefore it may have a shape and size different from that shown in the figures,

and in some cases the core may be entirely omitted, the blade consisting exclusively of the root and the straps wound upon the same. That is to say, the blade consists of a body and tension straps, the body includes a root member and it may include a core also. The core, however, is not essential and the root member may constitute the complete body without it.

The straps are made from a material of high tensile strength. They may be made from metal, but I prefer to make them from wood veneer in which the grain runs longitudinally of the straps, so that the high tensile strength longitudinally of the veneer is made use of.

In the figures I have shown only one ply of longitudinal strap 6, 6' and one ply of transverse straps 5. But it will be understood that a suitable number of plies is provided, in accordance with the desired tensile strength depending on the centrifugal force.

I claim:

1. A blade for propellers for air craft, comprising a root having a flat tapering portion and shaped to provide a transverse shoulder, a core engaging the opposite sides of said flat tapering

portion, a strap of high tensile strength wrapped transversely around the portion of the core engaging said tapering portion of the root, and a plurality of straps of high tensile strength wrapped around said shoulder and extending longitudinally of the blade.

2. A propeller blade including a root adapted to be fixed at its inner end to a hub and having at its outer end a widened outwardly tapering portion with transverse shoulders at the inner edge, a core secured to the outwardly tapering portion of the root, and tension straps wrapped upon the said shoulders of the widened outwardly tapering portion of the root and overlying the opposite faces of the core.

3. A propeller blade that includes a body and tension straps laid thereon, the body including a root that comprises a stem adapted at its inner end to be secured to a hub and at its outer end widened in a flat outwardly tapering portion with transverse shoulders at the inner edge, the tension straps being wrapped upon said shoulders and extending thence outwardly upon the body.

HEINRICH SUKOHL.
